(Cl. D15—3)

To all whom it may concern:

Be it known that we, Carroll W. Johnson and John T. Clark, citizens of the United States, residing at Chicago and Cicero, respectively, in the county of Cook and State of Illinois, have invented a new, original, and ornamental Design for a Combined Operator's Stool and Control for Dental Chairs, of which the following is a specification, reference being had to the accompanying drawing, forming part thereof.

In the drawing:

Figure 1 is a perspective view of a combined operator's stool and control for dental chairs, showing our design; and

Figure 2 is a plan view of the same.

We claim:

The ornamental design for a combined oper-

ator's stool and control for dental chairs, as shown.

CARROLL W. JOHNSON.
JOHN T. CLARK.
